PUMP POINT

Benjamin R. Tryce, Greenwood, Del.

Application May 11, 1939, Serial No. 273,154

1 Claim. (Cl. 166—5)

The present invention relates to new and useful improvements in pump points and has for its primary object to provide, in a manner as hereinafter set forth, a device of this character embodying novel means for filtering the fluid entering the device.

Another view important object of the invention is to provide a pump point of the aforementioned character comprising unique means for securing the filtering element in position.

Other objects of the invention are to provide a pump point of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in vertical section through a pump point constructed in accordance with the present invention.

Figure 2 is a bottom plan view of the device.

Figure 3 is a view in horizontal section, taken substantially on the line 3—3 of Fig. 1.

Referring now to the drawing in detail, it will be seen that the embodiment of the invention which has been illustrated comprises a metallic tube 1 of suitable length and diameter. The tube 1 is provided with a threaded upper end portion 2 for connection with the usual well tubing. The tube 1 is further provided with a multiplicity of circular openings or perforations 3.

Mounted on the lower end of the tube 1 is a metallic drive point 4. Rising from the point 4 is a neck 5 which is engaged in the lower end portion of the tube 1. Thus, a shoulder 6 is provided which the lower end of the tube abuts. A rivet 7 extends through the lower end portion of the tube 1 and the neck 5 for firmly securing the point 4 on said tube 1.

Mounted diametrically in the upper portion of the tube 1 above the openings or perforations 3 is another rivet 8. The reference numeral 9 designates a filtering element in the form of a

sponge which is mounted in the tube 1 on a supporting member in the form of a rod 10 which is made from a length of wire twisted on itself and terminating, at its ends, in loops or eyes 11 through which the rivets 7 and 8 pass.

In assembling the device the point 4 is mounted on the lower end portion of the tube 1 and the rod 10, with the sponge 9 thereon, is inserted in said tube. With the loops 11 aligned with the openings provided for the rivets 7 and 8, 10 said rivets are inserted and headed or upset, thus positively securing the filtering element in position. It will be observed that the rivet 7 constitutes common means for securing the point 4 and the lower end portion of the wire rod 10. 15 Of course, fluid entering the tube 1 through the openings 3 passes through the sponge 9 and is filtered thereby. When the sponge 9 becomes wet it swells and substantially fills the openings 3. While the device is particularly intended for 20 use in wells it may, of course, be used as a filter in any other manner for which it may be found adapted and desirable, as on suction lines and other conduits.

It is believed that the many advantages of a 25 pump point constructed in accordance with the present invention will be readily understood and although a preferred embodiment of the device is as illustrated and described, it is to be understood that changes in the details of construction 30 and in the combination and arrangement of parts may be resorted to which will fall within the scope of the invention as claimed.

What is claimed is:

A pump point of the class described comprising 35 a tube having openings therein for the entrance of fluid, a point mounted on one end of the tube and including a tubular neck extending thereinto, a rivet extending through the tube and the neck for securing the point to said tube, a rivet 40 mounted in the other end portion of the tube, a rod of twisted strands of wire mounted longitudinally in the tube and including loops on its ends, the rivets passing through said loops for securing the rod in position in the tube, and a 45 sponge mounted on the rod, said sponge constituting a filtering element for the fluid.

BENJAMIN R. TRYCE.
